UNITED STATES PATENT OFFICE.

HENRY E. POEHLMAN, OF SAN FRANCISCO, CALIFORNIA, ASSIGNOR OF ONE-HALF TO
JOHN W. FRICKE, OF SAN FRANCISCO, CALIFORNIA.

HYDROSTATIC TOY.

1,014,975.

Specification of Letters Patent. Patented Jan. 16, 1912.

Application filed March 16, 1911. Serial No. 614,840.

To all whom it may concern:

Be it known that I, HENRY E. POEHLMAN, citizen of the United States, residing in the city and county of San Francisco and State of California, have invented new and useful Improvements in Hydrostatic Toys, of which the following is a specification.

This invention relates to amusement devices, and comprehends particularly a device designed to resemble a geographical form, intersected by a canal, through which may be operated miniature vessels.

The object of the present invention is to provide an inexpensive and amusing toy representing mountainous forms bisected by a canal or cut provided with divisions typifying locks, whereby miniature vessels may be conveyed from one portion of the toy representing the surface of one ocean through the canal to the ocean on the other side of the mountainous formation; and to provide in such a toy means for varying the level of the liquid on which the ships may float.

25 The invention consists of the parts and the combination and construction of parts as hereinafter more fully described and claimed, having reference to the accompanying drawings, in which—

30 Figure 1 is a plan view of the toy. Fig. 2 is an end view of the same. Fig. 3 is a longitudinal vertical section.

My invention comprehends the provision of a toy provided with a suitable trough or pan 2, of suitable proportions. The area of the pan may be formed of suitable material, such as pressed sheet-metal, papier-mâché, cement, or in fact any other material which will serve the purpose to represent 35 mountainous contours, as 3, which may be extended sufficiently high above the plane of the pan 2, in which water 4 may be placed, and preferably the mountainous contours are represented as being partially cut 40 away, as at 5, to bisect the land. The portion 5 of the irregular mountainous structure 3 is provided with a series of transversely movable gates 6 adapted to form locks having vertical longitudinal walls 7, 45 and these walls 7 are extended on each side, as at 8, to form locks of lower elevation than the lock walls 7. The lock walls 8 form extreme locks in the canal system, one adapted to be connected by a closable gate 9 with a 50 body of water on one side of the irregular mountainous structure 3, which water will

represent the Pacific ocean, and the other extreme lock 8 is closable by its respective gate 9, through which communication may be had to an ocean representing the Atlantic. 60

The depth of water in the pan 2 will be sufficient to float small vessels represented at 10, and which are of such width and length as to be passed into the extreme locks 8 when the closing gates 9 have been swung 65 or moved open. When thus opened, the water in one of the locks 8 will be made to assume the level of the water in one of the oceans.

One of the novel features of the present 70 toy is to provide a means whereby the level of the respective locks 8—8 and the locks between the walls 7—7, which are much higher than the locks 8—8, may be varied so as to permit one of the vessels 10 to move 75 into one lock, as at 8, from one of the oceans and then to change the level of the water in the lock 8 so that it will proximate the level 80 of the water in the adjacent lock 7, and again to provide means whereby the water in the lock 7 may be elevated to proximate the level of the water in the central portion 85 of the canal between the gates 6. Any appropriate means for accomplishing this variation in the level of the locks 7 and 8 may 90 be used, and a simple means for effecting this variation is represented here as a tank 11, of which there are as many as there are locks in the canal, which tank 11 is bodily movable and connected to its respective lock wall by a flexible connection, shown here as a hose 12, and when it is desired to elevate a vessel 10 from the level of one of the oceans in an egress lock 8, the tank 11 of that lock is elevated and a volume of water in the tank will flow into the lock 8 between its walls and the gates, closing the ends of the locks, which gates must 95 be closed before the tank 11 is moved so as to permit its contained water to discharge 100 into the stationary lock 8. Thus when a vessel 10 has been moved into one of the entrance locks 8 and the gate 9 of this lock has been closed, then the tank 11 may be elevated, causing the water contained in the 105 tank to flow by gravity into the lock 8 containing the vessel, and the elevation of the level of the fluid in the lock 8 will cause the vessel to rise vertically until it assumes a 110 plane in line with the water level in an intermediate lock between the walls 7. By this time the gate closing communication be-

tween the locks 7 and 8 may be opened, thus permitting the vessel to be moved from the lock 8 into the lock 7, after which the controlling gate may be closed and a tank 11 connected to discharge into the lock between the walls 7 may be elevated so that the water contained in the tank 11 may flow into its lock, lifting the level of the water and the ship.

10 When the level of the water in the lock between the walls 7 has approximately reached the level of the water in the central chamber between the gates 6, one of these gates may be opened and the ship moved from the lock 7 into the central lock, and the gate 6 on the opposite end of the central portion of the canal may be opened to allow the ship to be passed from the central prism of the canal into the next adjacent lock 7, 15 provided the level of the water in the lock 7 has been brought into line with the water in the central chamber. When the water level in one of the locks has been elevated by reason of the elevation of its respective tank 11 and the discharge of the water from this 20 tank into the lock, the water thus discharged into the lock is again returned to the tank 11 to lower the level of the lock by lowering again the tank 11, thus permitting the excess 25 or added water to flow back into the connected tank 11.

Thus it will be seen that by this toy a child is considerably amused in the movement of the ships to and fro through the 30 canal from one ocean to the other, and also is instructed in the hydrostatic action of fluids by reason of the increase or reduction of the volume of water in the several locks.

I do not wish to be limited to any particular form of gate structure whereby the several canals may be closed, nor do I wish to be limited to any particular form of means for causing a variation of elevation of water in the several locks, as manifestly instead of 40 varying the level of the water in the locks by the addition of a volume of water from a tank 11, I may use in lieu of the tanks 11 small pumps by which water may readily be pumped from one or the other of the 45 oceans into any of the locks. One tank 11 may be used to control all locks, if desired, 50 with valves for controlling the flow.

The novelty is equally adaptable as an educational device as it is as a toy.

55 Having thus described my invention, what I claim and desire to secure by Letters Patent, is—

1. An amusement device comprising a receptacle for liquid, irregular surfaces of suitable material and contour attached to the receptacle, a series of communicating passageways bisecting said irregular surfaces, means for closing communication

between said passageways, and means for varying the level of the liquid within the 65 passageways.

2. An amusement device comprising a receptacle for liquid, irregular surfaces of suitable material and contour attached to the receptacle, a series of communicating passageways of various elevations bisecting said irregular surfaces, means for closing communication between said passageways, and means for varying the level of the liquid within the passageways. 75

3. An amusement device comprising a receptacle for liquid, irregular surfaces of suitable material and contour attached to the receptacle, a series of communicating passageways of various elevations bisecting said irregular surfaces, means for closing communication between said passageways, and means for varying the level of a liquid within the several passageways. 80

4. An amusement device comprising a receptacle for liquid, irregular surfaces of suitable material and contour attached to the receptacle, a series of communicating passageways of various elevations bisecting said irregular surfaces, means for closing communication between said passageways, and means for varying the level of a liquid within the several passages, said means including devices connected to respective passageways, whereby a volume of liquid may be added to the fluid already contained in the passageways. 85 90

5. A device comprising a receptacle adapted to contain liquid, vessels floatable upon said liquid, irregular surfaces representing mountainous or hilly country, and a series of passageways representing canal locks at different elevations bisecting the aforesaid irregular surfaces through which said vessels may be moved, and means for varying the level of the liquid within the passageways. 95 100

6. A device comprising a receptacle adapted to contain liquid, vessels floatable upon said liquid, irregular surfaces representing mountainous or hilly country, a series of passageways representing canal locks at different elevations bisecting the aforesaid irregular surfaces, through which said vessels may be moved, means whereby communication between the several locks may be controlled, and means for varying the elevation of liquid in the locks. 110 115 120

In testimony whereof I have hereunto set my hand in the presence of two subscribing witnesses.

HENRY E. POEHLMAN.
